UNITED STATES PATENT OFFICE.

ELON A. MARSH, OF DETROIT, MICHIGAN, ASSIGNOR TO FRANK G. O'HARA, OF DETROIT, MICHIGAN.

FLUSH-VALVE.

No. 805,148.

Specification of Letters Patent.

Patented Nov. 21, 1905.

Application filed May 31, 1904. Serial No. 210,613.

To all whom it may concern:

Be it known that I, ELON A. MARSH, a citizen of the United States, residing at Detroit, county of Wayne, State of Michigan, have 5 invented a certain new and useful Improvement in Flush-Valves; and I declare the following to be a full, clear, and exact description of the invention, such as will enable others skilled in the art to which it pertains to 10 make and use the same, reference being had to the accompanying drawings, which form a part of this specification.

This invention relates to flush-valves for tanks or cisterns, and has for its object an improved method of sustaining a vertically-lifting valve upon a support which by itself is 15 unstable, but when operated on by water flowing through the valve-seat becomes stable during the time such flow continues or until 20 the hydraulic head of water in the tank becomes so low and the current force so weak that the weight of the valve disengages the locking mechanism of the said support and permits the valve to fall freely on its seat.

25 I am aware that flush-valves have been devised and patented where mechanism in the outlet-passage below the valve-seat was operated by water flowing through the valve-seat to hold a hinged or flapper valve open 30 while the tank is flushing; but in such cases the valve and the locking mechanism are usually coupled together and are at all times liable to sustain the valve in an intermediate position with danger of less than a full or desired 35 opening. Moreover, such valves cannot fall freely by gravity, as in falling they must carry the locking or supporting mechanism in a contrary direction, and are therefore liable to fail to close perfectly. I am also aware that Letters Patent No. 758,012, issued to me on April 40 19, 1904, shows a device in which a catch is thrown by the weight of water to a position to engage under a part of the valve and suspended on a post.

45 In the drawings, Figure 1 shows the valve and the valve-casing, into which there is a waste-pipe connection at one side. Fig. 2 shows a plan view of the valve-casing and the location and arrangement of the interlocking 50 device for holding the valve above its seat.

In Fig. 1, 1 indicates the valve-casing or spud with a waste connection or overflow 2. At the top of the casing is a valve-seat 3, into which engages a flexible valve 4, surrounding

the valve-holder 5. Within the valve-casing 55 is a vertically-disposed cylindrical guide 6. Said guide is centrally attached to a cross-bar of the valve-casing and projects downward toward the bottom of the spud. A spindle or valve-stem 7, attached to the valve-holder 5, 60 is adapted to move freely in the guide 6 and guides the movements of the valve. The valve-stem 7 is provided with an annular circumferential groove 8. The upper side of this groove is slightly beveled and forms in part the supporting means for the valve. 65

9 indicates a curved vane attached to a lever 10, which is pivoted to the cross-bar by the pivot 11 and has an easy but limited oscillatory movement on a vertical axis. The lever 70 10 swings partly over the top of the guide 6 and engages or can engage in the groove 8 and support the valve.

The top of the valve is provided with an attachment for lifting it. 75

The operation of this valve is as follows: When the valve is lifted from its seat and water flows through the valve-orifice and strikes the curved vane 9 and swings lever 10 against the valve-stem, and if the valve is 80 raised to a point giving a desired valve-opening, so that the groove 8 registers with the lever 10, said lever will be pressed into said groove by the action of water on the curved vane and will support the valve so 85 long as the force of the flowing water is sufficient to maintain the engagement of the lever with the groove. As the upper face of the groove 8 is beveled, the weight of the valve tends at all times to push the lever away and 90 destroy its support, and when the force of water acting on the vane 9 is less than the opposing force of gravity the interlocking devices disengage and the valve falls freely 95 to its seat independently of the supporting mechanism.

It is evident that the elements of this invention may be employed in various forms without departing from well-established principles of mechanical equivalents. For instance, a supporting-lug may be attached rigidly to the guide or casing and a movable part actuated by water attached to the valve, or the valve itself may be provided with one or more wings or vanes that acted upon by water turn the valve or a part of the valve axially, and thus engage the mechanism of support; but such mechanical arrangements 100 105

would simply be another application of the elements of which I claim to be the original inventor.

I therefore claim as follows:

- 5 1. In a flush-valve for tanks or cisterns, a valve-casing and a valve-seat, a manually-opened valve provided with means for engaging with a support, a locking mechanism therefor that oscillates on a vertical axis and is actuated by water flowing through the valve-orifice, said valve being disengaged from its support by gravity when the flow of water through the orifice ceases, or is sufficiently weakened by the loss of hydraulic head, substantially as described.
- 10 2. In a flush-valve, the combination of a casing having a valve-seat at its upper face, a valve, a central vertical downwardly-extending stem for said valve, a sleeve in said casing for guiding said stem, and means hinged to said sleeve to contact with said stem and hold the valve in its elevated position.
- 15 3. In a flush-valve for tanks or cisterns, a valve-casing and a valve-seat, a valve therefor adapted to be raised or opened manually, a vertical guide for said valve having a supporting lug or catch to retain the valve in an open position; mechanism adapted to oscillate on a vertical axis and operated by the outflowing water to engage said lug or catch until the hydrostatic head is so reduced that its force is no longer sufficient to maintain an engagement of the supporting mechanism, whereby the weight of the valve disengages the supporting mechanism and the valve falls freely to its seat by gravity, substantially as described.
- 20 4. A flush-valve operated to open manually, a catch mechanism adapted to oscillate on a vertical axis actuated by the outflowing wa-
- 25 5. In a flush-valve for tanks or cisterns, a valve arranged to be opened manually, a supporting device for said valve formed in part by a vane or vanes adapted to turn on a vertical axis and upon which water flowing through the valve-orifice impinges, causing said support to become stable while water is flowing and permitting the valve to fall freely by gravity when the water ceases to flow, or when its flow is so reduced by the loss of hydraulic head that its force upon the vane is insufficient to maintain a stable support for the valve, substantially as described.
- 30 6. In a flush-valve for tanks or cisterns, a valve arranged to be opened manually and means for supporting the valve vertically above its seat by force of water flowing through valve-orifice, a spoon or vane oscillatory on a vertical axis adapted to actuate the supporting means or vane-shaped face or faces, under force of water causing said valve to rest on a support, which support is so arranged as to cause said valve to be released and permit said valve to fall to its seat by force of gravity as soon as the head of water in the tank or cistern is reduced below a predetermined point, substantially as described.

- 40

In testimony whereof I sign this specification in the presence of two witnesses.

ELON A. MARSH.
